UNITED STATES PATENT OFFICE

CHARLES E. SMITH, OF OROVILLE, CALIFORNIA

AEROPLANE PROPELLER

Application filed September 5, 1928. Serial No. 304,043.

This invention relates to an aeroplane propeller, and it is of the type of the helical flat blade propeller, with a propeller symmetrically placed upon each side of the engine, 5 with respect to the wings of the aeroplane. The propellers are carried by a single shaft which shaft is operated upon at its center by the engine to rotate it. The blades of the propeller are reversely arranged so that 10 the air is taken into the propeller adjacent to the engine, directed laterally and of course, as it leaves the propeller travels leewardly with respect to the planes.

Another object of the invention is to provide 15 means whereby the propulsive effect of the propeller may be regulated by covering or uncovering a portion of the spiral blade, of each propeller, there being an independently movable hood over each propeller to 20 effect this result, as well as to aid in turning the machine.

It will be understood that as the present 25 invention relates only to the propeller that any desired operating controls may be used in connection with the machine, but such controls do not form a part of the present invention and are hence not illustrated. The propellers may have one, two or more blades 30 as desired.

Other objects of the invention will appear 35 as the description proceeds. But in the accompanying drawings, Figure 1 is a plan view of the complete aeroplane with a portion of the upper wing broken away for purpose of illustration.

Figure 2 is a side elevation of the complete 40 aeroplane.

Figure 3 is an enlarged view of a portion 45 of the upper wing.

Figure 4 is an enlarged view of a portion of the propeller adjacent to the engine the movable shell being thrown back to show the propeller blade.

The numerals 1 and 2 indicate the ground 50 wheels of the aeroplane, which ground wheels are connected to the fuselage 3 by means of suitable struts 4 and 5 in such number as may be requisite. At the rear of the tail of the fuselage there is the sprag 6, to aid in bringing the aeroplane to earth when

it lands. On each side of the fuselage there is a lower wing as indicated at 7 and 8. These wings are connected to the fuselage at their inner ends and there are suitable other struts as indicated at 9 and 10, with bracing wires 11 and 12, in such number as may be requisite to give the necessary stiffness to the machine and to the upper wing 13.

The upper wing 13 has the movable ailerons 14 and 15 at the back edges, common to the art and at the center it is provided with a space to receive the engine cylinders 16. The engine is supported by two braces 18 and 19 which serve to connect it to the front edge of the wings 13, and to the braces 9 on opposite sides of the engine.

Extending laterally from both sides of the engine there is a shaft 20. Said shaft having flat spiral propeller blades on them as indicated at 21, 22, and so arranged as to cause the air impinging upon the blades at the center to travel longitudinally thereof and to be discharged from the propeller either downwardly or at their end. The propeller shaft is journaled in bearings 23, 23' at the inner ends of the propeller while they are carried by journals 24, 24' at their outer ends. The propellers are journaled at the front edge of the upper wing and extending longitudinally thereof. Both wings are of the parabolic type, which are thicker at their front edge than at any other portion, and in the present case they are slightly thicker than usual to produce a more or less cylindrical chamber within which the propeller blades are installed. This cylindrical chamber is provided with the shell 27 at its top above the propeller and in addition there is the movable cylindrical shell 28, 28' over each propeller.

The movable cylindrical shells are for the purpose of acting as guards to reduce the quantity of air impinging upon the propellers and they are held normally in the position shown in Figure 3, by means of the stiff springs 29, 29' which tend to pull the levers 30, 30' up to the normal position. The levers 30, 30' are ordinarily connected to the control apparatus of the aeroplane none of which is shown in the present instance.

The operation of the apparatus is substantially as follows: With an aeroplane equipped with suitable controls, the engine is started and the propellers thus are rotated with the result that air is taken rapidly from the position near the engine and extended laterally. The paddling of the air with the propellers being sufficient to cause it a slight lift. If the speed forward be fast enough the aeroplane will travel over ground fast enough to lift itself and gradually soar away.

The cables and other controls for operating the machine are not illustrated as they form no part of the present invention.

15 What I claim as new and desire to secure by Letters Patent of the United States is as follows, express modifications being reserved of matter within the scope of the claims appended hereto.

20 1. An aeroplane propeller comprising an aeroplane having supporting wings, a right and left spiral blade propeller each installed adjacent to and on each side of the longitudinal center of the upper wing and having a 25 pocket within which said propellers can operate, said propellers being placed upon a wing axis parallel to the length of the wing at the front of the same, and an engine centrally placed to drive both of said propellers.

30 2. An aeroplane of the type described, having a pair of supporting planes, an engine whose axis is substantially in alignment with the upper of said planes, a screw propeller carried by the engine axle on both sides of 35 the engine, and a cylindrical casing partially enclosing each propeller with means for resiliently holding said movable casing up while permitting it to be pulled downwardly to partially cover the corresponding aeroplane propeller.

40 3. An aeroplane propeller of the class described comprising an aeroplane wing, means to mount a rotatable shaft along the front edge of said wing, an engine adapted to turn said shaft, a right and left spiral blade propeller on each end of said shaft, a stationary hood adapted to cover the upper portion of said propeller, a hood pivoted on said shaft and normally covering the upper portion of 45 said propellers, and means to rotate said hood down to cover more or less of the propeller blades.

4. An aeroplane propeller comprising a driven shaft arranged in alignment with the 50 front edge of the plane wing, oppositely directed spiral vanes on the opposite ends of said shaft respectively, hoods extending from the edge of said wing over the upper portion of said vanes, casings within said hoods 55 adapted to be extended beneath the lower portion of said vanes.

5. An aeroplane propeller comprising a driven shaft arranged in alignment with the front edge of the plane wing, oppositely 60 directed spiral vanes on the opposite ends of

said shaft respectively adapted to operate in concave chambers in said wing overhanging the upper portion of said vanes, and cylindrical casings adapted to cover the lower portions of said vanes.

6. In combination with an aeroplane having a wing with a longitudinal chamber in the front edge thereof, a propeller in said chamber and means for opening and closing the lower portion of said chamber.

In testimony whereof I have hereunto set my hand this 30th day of August, A. D. 1928.

CHARLES E. SMITH.
